UNITED STATES PATENT OFFICE.

EDWARD O. STERNS, OF COLUMBUS, OHIO, ASSIGNOR TO THE ROTARY TIRE AND RUBBER COMPANY, OF ZANESVILLE, OHIO, A CORPORATION OF OHIO.

DESIGN FOR A PNEUMATIC TIRE.

55,141.

Specification for Design.

Patented May 11, 1920.

Application filed May 8, 1919. Serial No. 295,783. Term of patent 14 years.

To all whom it may concern:

Be it known that I, EDWARD O. STERNS, a citizen of the United States, residing at Columbus, in the county of Franklin, State of Ohio, have invented a new, original, and ornamental Design for Pneumatic Tires, of which the following is a specification, reference being had to the accompanying drawing, forming a part thereof.

Figure 1 is an edge view of a tire, showing my new design.

Fig. 2 is a similar view of a portion thereof on a larger scale.

I claim:

The ornamental design for a pneumatic tire as shown.

EDWARD O. STERNS.
